1

AROMATIC ACET AMIDOXIME-O-CARBAMATES

CROSS REFERENCE TO RELATED APPLICATIONS

This application is related to my earlier filed patent application Ser. No. 884,737, filed Dec. 12, 1969, which is a continuation-in-part of my application Ser. No. 789,959, filed Jan. 8, 1969 both of which are now 10 abandoned.

BACKGROUND OF THE INVENTION

Field of the Invention

This invention relates to a novel class of amidoxime-O-carbamates useful as antihypertensive or antiinflammatory agents.

Prior Art

Amidoxime-O-carbamate compounds have been known since the work of Tiemann and Kruger [Ber. 17, 25 1685 (1884)]. The authors erroneously reported the compounds shown in their article as being oximes of ureides. R. Bryle, F. Eloy and R. Lanaers [Helv. Chim. Acta, 46, 1073 (1963)] later demonstrated that Tie- 30 mann and Kurger's reaction actually leads to O- carbamates of amidoximes and reported on a series of such compounds which they prepared. These prior art compounds are not known as being antihypertensive or antiinflammatory agents and differ structurally from the class of amidoxime-O-carbamates constituting the 35 present invention.

Bell et al. [Experientia, 23, 298 (1967)] and Hoppe et al. [Fed. Proc., 26, 459 (1967)] have reported certain indoleacetamidoximes as having antihypertensive activity in rats and dogs. The amide-O-carbamates of 40 the present invention also differ structurally from these prior art compounds, being simpler and less costly to prepare.

SUMMARY OF THE INVENTION

The invention relates to a compound selected from the group (A) having the formula

wherein

R and R³, alike or different, are H or alkyl of up to three carbon atoms;

R^1 and R^2 , alike or different, are H or alkyl of up to 60 three carbon atoms with the proviso that the sum of their carbon atoms does not exceed three:

Q is

a. an aryl radical of up to 12 carbon atoms; such aryl radical substituted with Br, Cl, F, I, NO₂, CN, or lower alkyl, alkoxy, alkanoyl or (dialkylamino)alkyl; or

(B) the pharmaceutically acceptable salts of (A). "Lower" is taken to mean one to three carbon atoms. Pharmaceutically acceptable salts of the above compounds are also included within the scope of this invention. Such salts are obtained from pharmaceutically acceptable acids. Illustrative of such salts are the hydrochloride, hydrobromide, sulfate, phosphate and nitrate salts.

35 Preferred compounds within the scope of the above definition are those wherein Q is phenyl, thiaryl or phenyl substituted with methyl, methoxy, F, Cl, or NO_2 ; R, R^1 and R^3 are H; R^2 is methyl.

Another embodiment of the invention relates to a method for treating hypertension in warm-blooded animals which comprises administering to said animal an antihypertensive amount of a compound of the invention.

A further embodiment relates to pharmaceutical compositions containing a compound of the invention in combination with suitable pharmaceutical adjuvants and modifiers.

The compounds of the invention are readily prepared from intermediates made according to the general procedure of F. Tiemann, Ber. 17, 126 (1884) which may be represented by equation (1) below:

55 The acetamidoxime-O-carbamates of the invention, where $R^1 = R^2 = H$, are conveniently prepared by reaction of the amidoximes of equation (1) in salt form, such as the hydrochloride salt, with an alkali metal cyanate as shown by equation (2) below:

where X = an anion, e.g., chloride, bromide, sulfate, phosphate or nitrate and M is a monovalent alkali metal cation.

The reaction of equation (2) is conducted in aqueous solution at a temperature between about 0°–50°C. and is generally complete in 15 minutes to three hours. Longer reaction times can be used but are not generally necessary.

The acetamidoxime-O-carbamates of the invention, wherein R^1 or R^2 is alkyl, are prepared by reacting acetamidoximes of equation (1) with an isocyanate according to equation (3) below:

The reaction of equation (3) is readily effected by stirring the amidoxime of equation (1) in a suitable solvent such as dioxane, tetrahydrofuran, ethyl acetate, chloroform, diethyl ether, benzene, or the like, while adding the isocyanate at a rate to maintain temperatures from 0°–50°C. The reaction is generally complete in about 5 hours; however, some reactions are vigorous enough to be completed in about 0.5 hour. The products are sufficiently stable under reaction conditions that longer reaction times, e.g., up to 24 hours, do no harm and, for convenience, reaction periods lasting overnight can be used.

The acetamidoxime-O-carbamates of the invention wherein both R^1 and R^2 are alkyl, are prepared by reacting the acetamidoximes of equation (1) with a carbamoyl chloride according to equation (4) below:

In equation (4) any carbamoyl halide can be used in place of the carbamoyl chloride shown. For example, one can use the carbamoyl fluoride, bromide or iodide but for economy and convenience the carbamoyl chloride is generally preferred.

The use of a base is not essential but when used may be any convenient acid-accepting compound that will combine with the acid by-product of the reaction. One may use alkali metal and alkaline earth metal oxides, hydroxides, carbonates and bicarbonates. Organic bases such as pyridine, quinoline, trialkylamines, and the like, are similarly useful.

The reaction of equation (4) is effected by adding the carbamoyl halide to the amidoxime in a suitable inert

solvent such as dioxane, chloroform, diethyl ether, carbon tetrachloride, or the like. The reaction is conducted at a temperature between room temperature, i.e., about 25°C, and the solvent reflux temperature, for a period of time between about 15 minutes and five hours or longer.

The salts of the amidoxime-O-carbamates of the invention can be prepared by treating a solution of the compound with the acid of the salt desired. The solvent can be selected to provide a system in which the salt formed is insoluble and therefore easily separated from the solution. Alternatively, a solvent system in which the end product salt is soluble can be employed and the solvent can be removed by evaporation.

In general, the salts of the amidoxime-O-carbamates of the invention hydrolyze readily and thus are less desirable for use in formulating pharmaceutical compositions of the invention than the amidoxime-O-carbamates per se.

SPECIFIC EMBODIMENTS OF THE INVENTION

The preparation of the compounds of this invention is illustrated but not limited by the following examples in which all parts are by weight unless otherwise stated.

EXAMPLE 1

o-Tolylacetamidoxime-O-(N-methylcarbamate)

To a chilled solution (10°–15°C) of 16.2 g (0.1 mole) of *o*-tolylacetamidoxime in 100 ml of benzene was added dropwise 5.7 g (0.1 mole) of methyl isocyanate in 25 ml of benzene. The solution was stirred for 1 hour, concentrated under vacuum and the resulting solid was filtered and recrystallized from ethyl acetate. This yielded 10.03 g (46 percent) of the carbamate as a white solid melting at 115.5°–116.2°C.

* Compound as HCl salt.

EXAMPLE 10

o-Tolylacetamidoxime-O-(N,N-dimethylcarbamate)

A solution of 24.0 g (0.15 mole) of o-tolylacetamidoxime, 16.0 g (0.15 mole) of dimethylcarbamoyl chloride and 16.0 g (0.16 mole) of triethylamine in 300 ml of chloroform was heated at reflux for four hours, concentrated, filtered and the precipitate was washed with water. This yielded a white solid which after recrystallization from benzene-cyclohexane gave 23 g (66 percent) of o-tolylacetamidoxime-O-(N,N-dimethylcarbamate) melting at 123.2-123.8°C.

Found: C, 61.54; H, 7.56; N, 17.77.

Other arylacetamidoximes that can be prepared as described above include:

7

The compounds of this invention can be administered in the treatment of hypertension and of inflammatory disease, as for example rheumatoid arthritis, by any means that effects contact of the active ingredient compound with the site of action in the body of a warm-blooded animal. For example, administration can be parenterally, i.e., subcutaneously, intravenously, intramuscularly, or intraperitoneally. Alternatively or concurrently, administration can be by the oral route.

The dosage administered will be dependent upon the age, health and weight of the recipient, the extent of disease, kind of concurrent treatment, if any, frequency of treatment and the nature of the effect desired. Generally, a daily dosage of active ingredient compound will be from about 0.01 to 50 mg/kg of body weight. Ordinarily, from 0.05 to 40 and preferably 0.1 to 20 mg/kg per day in one or more applications per day is effective to obtain desired results. For the more potent compounds of the invention, e.g., p-chlorophenylacetamidoxime-O-(N-methyl carbamate), the daily dosage ranges from about 0.01 to 20 mg/kg, preferably 0.05 to 10 mg/kg, and more preferably 0.1 to 5 mg/kg.

The antihypertensive activity of the amidoxime-O-carbamates of the invention is evidenced by tests conducted in hypertensive rats and by further tests which show a blood pressure lowering action in normotensive dogs.

In a test involving rats, made hypertensive by repeated injections of desoxycorticosterone acetate (DOCA) according to the method described by Stanton and White [Arch. Intern. Pharmacodyn., 154, 351 (1965)], an acetamidoxime-O-(N-methylcarbamate) is injected intraperitoneally (i.p.) or orally into each of nine test animals on a cumulative dose schedule using three doses separated by a three-fold increment. The compound is prepared in an aqueous polyvinyl alcohol-acacia vehicle and administered at a volume to body weight ratio of 5.0 ml/kg.

The first dose level is administered immediately after a control blood pressure reading, with the second and third levels following 2-hour and 4-hour blood pressure determinations, respectively. Systolic blood pressure is determined by a modification of the microphonemometer technique [Friedman, M. and Freed, S. C., Proc. Soc. Exp. Biol. and Med. 70, 670 (1949)].

It is determined as a result of the test that 8 mg/kg of the compound p-chlorophenylacetamidoxime-O-(N-methylcarbamate) produces a 30 mm mercury (mm Hg) reduction in blood pressure from the pre-dose control value intraperitoneal (Effective Dose 30). Other compounds of the invention tested in a similar manner also show a significant activity in reducing blood pressure. For example, in the same test procedure it is determined that the intraperitoneal Effective Dose 30 value (i.p. ED₃₀) for 2,4,6-trimethylphenylacetamidoxime-O-carbamate is 7 mg/kg and for 4-fluorophenylacetamidoxime-O-(N-

methylcarbamate) the i.p. ED₃₀ value is less than 10 mg/kg.

The antiinflammatory activity of the amidoximecarbamates of the invention is evidenced by the inhibition of carrageenin-induced edema in the hind paw of rats in tests done according to the method of Winter, Risley and Nuss [Proc. Soc. Exp. Biol. and Med. 111, 544 (1962)].

10 Amidoximecarbamates of the invention were administered to male Carworth Farms CFE rats weighing about 100 grams by intubation as a solution in a PVA-Acacia medium (polyvinyl alcohol 1 percent, acacia 5 percent and methylparaben 0.1 percent) at a volume of 1 ml per 100 grams of body weight. Uniform hydration was provided by an additional volume of water equal to 2 ml per 100 grams of body weight. Each compound was administered orally at 300 mg/kg to six rats.

One hour after drug treatment, 0.5 ml of 1 percent 20 carrageenin solution was injected into the plantar region of the right-hind paw of each rat. The volume of the foot was measured immediately after injection and again three hours later. The difference between the two 25 volumes was the volume of induced edema. Foot volume was measured by immersion in mercury to an ink mark on the lateral malleolus. The mercury column was connected via a hydraulic system to a strain gauge. The output of the transducer was led to a Sanborn Transducer Amplifier, which was calibrated in terms of 30 mercury displacement.

It is determined as a result of the test that compounds of the invention showed significant antiinflammatory activity as evidenced by the reduction in the volume of 35 carrageenin-induced edema. For example, 300 mg/kg of the compound p-chlorophenylacetamidoxime-O-(N-methylcarbamate) produced a 90 percent reduction in induced edema, 300 mg/kg of the compound 2,4,6-trimethylphenylacetamidoxime-O-carbamate produced a 39 percent reduction in induced edema, and 300 mg/kg of the compound 4-fluorophenylacetamidoxime-O-(N-methylcarbamate) produced an 81 percent reduction in induced edema.

40 The compounds of this invention can be employed in useful pharmaceutical compositions in such dosage forms as tablets, capsules, powder packets or liquid solutions, suspensions or elixirs for oral administration or liquid for parenteral use, and in certain cases, suspensions for parenteral use (except intravenous injections). In such compositions, the active ingredient will 45 ordinarily be present in an amount of at least 0.5 percent by weight based on the total weight of the composition and not more than 90 percent by weight.

50 Besides the active ingredient compound of this invention, the antihypertensive or antiinflammatory composition will contain a solid or liquid nontoxic pharmaceutical carrier for the active ingredient.

In one embodiment of a pharmaceutical composition of this invention, the solid carrier is a capsule which can be of the ordinary gelatin type. In the capsules will 55 be from about 5-90 percent by weight of a compound of the invention and 95-10 percent of a carrier. In another embodiment, the active ingredient is tableted with or without adjuvants. In yet another embodiment, the active ingredient is put into powder packets and employed. These capsules, tablets and powders will generally constitute from about 1 percent to about 95 percent and preferably from 5-90 percent by weight of active ingredient. These dosage forms preferably con-

tain from about 5 to about 500 mg of active ingredient, with about 7 to about 250 mg most preferred.

The pharmaceutical carrier can, as previously indicated, be a sterile liquid such as water and oil, including those of petroleum, animal, vegetable, and oils of synthetic origin, e.g., peanut oil, soybean oil, mineral oil, sesame oil, and the like. In general, water saline, aqueous dextrose (glucose) and related sugar solutions and glycols such as propylene glycol or polyethylene glycols are preferred liquid carriers, particularly for injectible solutions. Sterile injectible solutions such as saline will ordinarily contain from about 0.5-25 percent and preferably about 1-10 percent by weight of the active ingredient.

As mentioned above, oral administration can be in a suitable suspension or syrup, in which the active ingredient ordinarily will constitute from about 0.7-10 percent and preferably about 1-5 percent, by weight. The pharmaceutical carrier in such composition can be a watery vehicle such as an aromatic water, a syrup or a pharmaceutical mucilage.

Suitable pharmaceutical carriers are described in "Remington's Pharmaceutical Sciences" by E. W. Martin, a well known reference text in this field.

Representative test data on the preferred antihypertensive or antiinflammatory agents of this invention are summarized in Table II where the data for the I.P. ED₅₀ column were obtained when the compounds were tested on rats by the method of Stanton and White previously mentioned. The data for the percent Edema Reduction was obtained when the compounds were tested as previously described.

*These represent the full structural formulas rather than the segment Q.

The following are illustrative examples of pharmaceutical compositions containing a compound of the invention.

EXAMPLE 11

Tablets are prepared using conventional procedures and equipment. Each tablet contains 100 mg. of p-chloro-phenylacetamidoxime-O-(N-methyl carbamate), 187.7 mg. mannitol, U.S.P., 0.3 mg. silicon dioxide, N.F., 3.0 mg. Povidone, N.F., and 9.0 mg. magnesium stearate, U.S.P.

Appropriate quantities of other tablet excipients may be used along with, or in place of, those mentioned above. For example, calcium stearate or stearic acid may be used as a lubricant, or talc may be used as a glidant or other binders such as "Methocel" or "Ethocel" may be used.

EXAMPLE 12

No. 1 hard gelatin capsules are filled so that each capsule contains 200 mg. of 2,4,6-trimethylphenylacetamidoxime-O-carbamate, 8 mg. of magnesium stearate, U.S.P., 32 mg. of talc, U.S.P. and 160 mg. of mannitol, N.F.

EXAMPLE 13

A mixture of 50 mg. of 4-fluorophenylacetamidoxime-O-(N-methyl carbamate) is prepared by milling the compound in 103 mg. soybean oil with 4 mg. of soy lecithin and 12 mg. of a mixture consisting of 1 part hydrogenated soybean oil, 1 part yellow wax, N.F. and four parts food grade vegetable shortening. The resulting suspension is used to prepare soft gelatin capsules by means of a positive displacement pump.

EXAMPLE 14

A parenteral composition suitable for administration by injection is prepared by dissolving 1 percent by weight of α -methyl-phenyl acetamidoxime-O-(N-methylcarbamate) hydrochloride in sodium chloride injection, U.S.P. The solution is sterilized by filtration.

The embodiments of the invention in which an exclusive property or privilege is claimed are defined as follows:

1. A compound selected from the group
  - A. having the formula

wherein

R and R³, alike or different, are H or alkyl of up to three carbon atoms;

R¹ and R², alike or different, are H or alkyl of up to three carbon atoms with the proviso that the sum of their carbon atoms does not exceed 3;

Q is

a. an aryl radical of up to 12 carbon atoms; such aryl radical substituted with Br, Cl, F, I, NO₂, CN, or lower alkyl, alkoxy, alkanoyl or (dialkylamino)alkyl;

B. salts thereof with pharmaceutically acceptable acids (A).

2. A compound of claim 1 wherein R, R¹ and R³ are H, R² is methyl, and Q is phenyl, or phenyl substituted with methyl, methoxy, F, Cl or NO₂.

3. A compound of claim 2 wherein Q is phenyl; phenylacetamidoxime-O-(N-methylcarbamate).

4. A compound of claim 2 wherein Q is o-tolyl; o-tolylacetamidoxime-O-(N-methylcarbamate).

5. A compound of claim 2 wherein Q is p-fluorophenyl; p-fluorophenylacetamidoxime-O-(N-methylcarbamate).

6. A compound of claim 2 wherein Q is p-chlorophenyl; p-chlorophenylacetamidoxime-O-(N-methylcarbamate).

7. A compound of claim 2 wherein Q is p-nitrophenyl; p-nitrophenylacetamidoxime-O-(N-methylcarbamate).

8. A compound of claim 2 wherein Q is 3,4-dimethoxy-phenyl; 3,4-dimethoxyphenylacetamidoxime-O-(N-methylcarbamate).

10

15

9. A compound of claim 2 wherein Q is 3,4-dimethylphenyl; 3,4-dimethylphenylacetamidoxime-O-(N-methylcarbamate).

10. A compound of claim 2 wherein Q is 2,4,6-trimethylphenyl; 2,4,6-trimethylphenylacetamidoxime-O-(N-methylcarbamate).

11. A compound of claim 1 wherein R and R² are each methyl, R¹ and R³ are each hydrogen, and Q is phenyl; α -phenylpropionamidoxime-O-(N-methylcarbamate).

12. A compound of claim 1 wherein R and R³ are each hydrogen, R¹ and R² are each methyl, and Q is o-tolyl; o-tolylacetamidoxime-O-(N,N-dimethylcarbamate).
